BATHROOM ACCESSORY CABINET OR SIMILAR ARTICLE

Daniel W. Witkin, Hewlett Harbor, N. Y.

Application June 1, 1954, Serial No. 30,744

Term of patent 14 years

(Cl. D4—3)

To all whom it may concern:

Be it known that I, Daniel W. Witkin, a citizen of the United States and a resident of Hewlett Harbor, New York, have invented a new, original, and ornamental Design for a Bathroom Accessory Cabinet or Similar Article, of which the following is a specification, reference being had to the accompanying drawing, forming a part hereof, in which

I claim:

The ornamental design for a bathroom accessory cabinet or similar article, as shown.
